[57] CLAIM

The ornamental design for a “medium duty bag closure with handle,” as shown and described.

DESCRIPTION

FIG. 1 is a perspective view of a medium duty bag closure with handle, showing my new design from above and in an open state;

FIG. 2 is a perspective view thereof, showing my new design from below and in an open state;

FIG. 3 is a perspective view thereof, showing my new design from above and in closed state;

FIG. 4 is a top plan view of FIG. 3;

FIG. 5 is a front elevational view of FIG. 3;

FIG. 6 is a bottom plan view of FIG. 3;

FIG. 7 is a rear elevational view of FIG. 3;

FIG. 8 is a left side elevational view of FIG. 3;

FIG. 9 is a right side elevational view of FIG. 3; and,

FIG. 10 is an enlarged sectional view taken along line 10—10 in FIG. 3.

The broken line environmental structure is for illustrative purposes only and forms no part of the claimed design.
